UNITED STATES PATENT OFFICE.

EDWIN J. HOUSTON, OF PHILADELPHIA, PENNSYLVANIA, ASSIGNOR TO
THE THOMSON-HOUSTON ELECTRIC COMPANY, OF CONNECTICUT.

ELECTRIC-ARC LAMP.

SPECIFICATION forming part of Letters Patent No. 307,769, dated November 11, 1884.

Application filed May 4, 1883. (No model.)

To all whom it may concern:

Be it known that I, EDWIN J. HOUSTON, a citizen of the United States, and a resident of Philadelphia, in the county of Philadelphia and State of Pennsylvania, have invented certain new and useful Improvements in Electric Lamps, of which the following is a specification.

My invention relates to a novel construction of the frames for electric lamps, whereby the insertion and adjustment of the upper and lower carbons in such lamps are greatly facilitated.

In placing the carbons in the carbon-holders of an electric lamp provided with a glass globe difficulty is experienced in adjusting the carbons in line with each other, especially if the globe is furnished with a top or cover.

The object of my invention is to avoid this difficulty in electric lamps; and to this end my invention consists of a lamp-frame of novel and simple construction, the peculiarities of which will be hereinafter described, and then specified in the claims.

Figure 1 is an elevation of a lamp-frame constructed according to my invention. Fig. 2 is a view of the frame, looking upward, and illustrating the position of the parts when the cross-bar is swung to one side to throw the carbons out of line. Fig. 3 is a side view, and Fig. 4 an edge view, of a modified form of the invention.

In Fig. 1, A illustrates the glass globe, mounted upon and securely fastened in any approved manner to the lower connecting-piece, B, to which, also, the lower carbon and carbon-holder, with proper electrical connections, are attached. This connecting-piece B, which is usually a continuation of the vertical arms C C², or, if made separate, is rigidly attached thereto, is made movable in this instance by providing a swivel-point, hinge, pivot, or joint—such as shown at D—in such a manner that the lower piece, B, with its appendages, may be turned outward in a horizontal plane into the position shown in Fig. 2 of the drawings. Half a revolution allows sufficient space to insert either carbon without interference with or from the other. The other end of the connecting-piece B is pro-

vided with a clamp-screw, E, to secure it to the arm C², when necessary.

Suitable locking devices—such as spring-catch F—may be employed in addition to the clamp-screw E, in order to guard against accidental unlocking of the latter. In order to stiffen and strengthen the lower ends of both arms C C², a semicircular brace-bar, G, is provided, which unites both arms in such a manner as to permit the connecting-piece B to partly overlap the same when in its proper position, and to serve as an additional support to the latter.

In the modification shown in Figs. 3 and 4 the lower connecting-piece, B, is pivoted at M and N to the ends of the vertical arms C C², so that it may be revolved in a vertical plane. A quarter of a revolution, as shown in Fig. 4 in dotted lines, is sufficient to remove the connecting-piece B and its appurtenances out of line with the upper carbon. The extent of this motion is limited by suitable stops. (Shown at O O².) A set-screw, P, serves to hold the piece B in any desired position in which it is placed, and any locking device—such as spring-catch Q—may be provided as an additional guard against accidental displacement of the lower carbon.

What I claim as my invention is—

1. The combination, in an electric-arc lamp, of the side rods, C C², and a pivoted cross-bar, B, carrying the globe that protects the arc, as and for the purpose described.

2. The combination, in an electric-lamp frame, of the side bars, C C², the permanent strengthening cross piece or bar G, and the jointed or hinged cross-bar B, as and for the purpose described.

3. The combination, in an electric-lamp frame, of the side bars, C C², the lower cross-piece, B, uniting said bars and hinged to swing in a plane at right angles to them, as and for the purpose described.

Signed at Philadelphia, in the county of Philadelphia and State of Pennsylvania, this 7th day of April, A. D. 1883.

EDWIN J. HOUSTON.
